UNITED STATES PATENT OFFICE.

HENRY G. VOIGHT, OF NEW BRITAIN, CONNECTICUT, ASSIGNOR TO RUSSELL & ERWIN MANUFACTURING COMPANY, OF NEW BRITAIN, CONNECTICUT, A CORPORATION OF CONNECTICUT.

PANIC-BOLT.

No. 919,269.

Specification of Letters Patent. Patented April 20, 1909.

Application filed February 27, 1909. Serial No. 480,297.

To all whom it may concern:

Be it known that I, HENRY G. VOIGHT, a citizen of the United States, residing at New Britain, county of Hartford, State of Connecticut, have invented certain new and useful Improvements in Panic-Bolts, of which the following is a full, clear, and exact description.

My invention relates to locks and particularly to the so-called panic bolt construction.

The object of my invention is to provide simple and effective mechanism embracing certain features whereby many advantages are gained.

In the drawings, Figure 1 is a fragmentary perspective view of a portion of a door illustrating my improved lock as it appears when applied thereto. Fig. 2 is a section of the door showing the appearance of the lock at opposite sides of said door. Fig. 3 is a view of the inner side of the case showing the interior mechanism. Fig. 4 is a section on the plane of the line $x-x$, Fig. 3, looking in the direction of the arrow. Fig. 5 is a detail view partly in section.

1 represents a door; 2 a lock case; 3—3^a are spring-projected bolts.

4 is a bracket carried by the lock case 2. 5 is an operating bar extending across the face of the door and arranged to move to and from the door, said bar being so connected that bolts 3—3^a will be withdrawn when said bar is moved in either direction, that is, toward or from the door.

6 is an outside bolt-operating device in the form of an ordinary knob with the usual mounting.

7 represents the end of a cylinder lock accessible at the outside and for dead-locking the mechanism against operation by the knob 6, said dead-locking mechanism being such that, when locked, the bolts 3—3^a may still be operated by the bar 5.

45 The bar 5 is carried at one end by a lever 8 mounted on pivot 9 in bracket 4. The other end of the rod 5 is carried by a link 8^a mounted on bracket 4^a carried by the door, so that the bar 5 will stand across the face of 50 the door, as best seen in Fig. 1.

The bolts 3—3^a may be provided with suitable guides or bearing boxes 3^b—3^b, the latter being secured to the door near the top and bottom. In Fig. 5, the locking end of 55 one of the bolts 3 is shown, and it will be

seen that contained within the housing or bearing 3^b is a spring 10 which is so connected with the bolt 3 as to normally project the same. The same sort of a spring is preferably provided for the lower bolt. 60

11 is a central pivot.

12 is a walking beam pivoted thereon.

13—14 are links connecting opposite ends of the walking beam 12 with the opposite bolts 3^a—3 respectively, as by a toggle 65 arrangement, said toggles being off center at all times and normally standing as shown in solid lines Fig. 3.

15 is a slide mounted in the lock case 2 and operatively connected as by pin 16 with one 70 end of the walking beam. The pin 16 may be carried by the end of the link 13 and passes through a radial-slot in the walking beam 12 and into a longitudinal slot in the slide 15. If the slide 15 is moved upwardly 75 from the position shown in solid lines (Fig. 3) to the position shown in dotted lines, it moves the pin 16 and all parts connected therewith. This movement is in a direction to withdraw the bolts 3—3^a. 80

17 is a pin carried by the link 14, which pin passes through a radial slot in the opposite end of the walking beam 12 and also stands in a recess in a sliding yoke 18. This yoke is provided with suitable guides in case 2. 85

19 is a roll back connected to and controlled by the outside knob 6 in the usual manner, said roll back 19 engaging the tail of the sliding yoke 18 in such manner as to permit said slide to be drawn back by the 90 operation of the knob 6. This movement of the sliding yoke 18 through its connection with the walking beam 12 causes the retraction of the bolts 3—3^a. 95

20 is a locking shoulder on the hub or roll 95 rack 19, which is arranged to be engaged by the dead-locking slide 21 mounted in the case 2 and arranged to be shifted by a key inserted in the cylinder lock 7. 100

22 is a tumbler carried by the slide 21.

23 is a roll back arm mounted on a roll back 24, which, when the parts are assembled, is in operative engagement with the outside lock 7.

As shown in Fig. 3, the roll back 19 is free 105 to be moved. If, however, the operator wishes to lock the door against admission from the outside, he simply inserts his key in lock 7 and turns the roll back hub 24 until the tumbler 22 is released, whereupon, by 110

the same means, the slide 21 is advanced to engage the locking nose 20 on roll back 19. Under these conditions, of course, the outer knob can not be turned and hence access 5 from the outside is prevented save by the use first of a proper key. This locking of the roll back hub 19 does not, however, affect the operation of the bolts 3-3^a, by the bar 5, which may still be retracted should the 10 walking beam 12 be operated.

Now, referring to Fig. 4, it will be seen that the slide 15 has a suitable bearing such as an anti-friction roller 25 at its forward side.

26 is a lever pivotally mounted in the 15 bracket 4, one end of said lever projecting under the roll 25. The lever portion 8 of the inside operating mechanism is provided with two horns 8^b-8^c, which stand above and below the lever 26 and at opposite ends 20 thereof. By reason of this arrangement, a movement of the operating bar 5 in either direction will tilt lever 26 so as to force the slide 15 upwardly, which movement, as before explained, operates the walking beam 12 25 to retract the bolts 3-3^a.

By having the pin 16 stand in a longitudinal slot in the slide 15, the walking beam may swing on its axis 11 without moving the slide 15, thus permitting said walking beam 30 to be operated by the sliding yoke 18.

27 is a spring, operating to normally hold the slide 15 retracted in the position shown in solid lines Fig. 3.

What I claim is:

35 1. In a panic bolt, a bolt member, means for normally projecting the same, two separate operating means for arrangement on opposite sides of a door; for independently retracting said bolt, one means arranged to 40 move toward or from the door for its operative movements and arranged on the inner side of the door, with connections between the last mentioned means and said bolt whereby either movement will cause the retraction of the bolt.

2. In a panic bolt, a bolt member, means for normally projecting the same, two separate operating means for arrangement on opposite sides of a door; for independently retracting said bolt, one means arranged to 50 move toward or from the door for its operative movements and arranged on the inner side of the door, with connections between the last mentioned means and said bolt whereby either movement will cause the retraction of the bolt, and means for dead-locking the other bolt operating means without interfering with the operation of the other bolt-operating means.

60 3. In a panic bolt, a pair of oppositely arranged bolts, means for normally causing

said bolts to remain projected, means for retracting said bolts comprising a walking beam, links connecting the same with both of said bolts, an operating device connected 65 with said walking beam and comprising a bar arranged transversely of the door, and means intermediate said bar and said walking beam whereby movement of said bar toward or from the door moves said beam in a 70 direction to retract said bolts.

4. In a panic bolt, a pair of oppositely arranged bolts, means for normally causing said bolts to remain projected, means for retracting said bolts comprising a walking 75 beam, links connecting the same with both of said bolts, an operating device connected with said walking beam and comprising a bar arranged transversely of the door, and means intermediate said bar and said walking beam whereby movement of said bar toward or from the door moves said beam in a direction to retract said bolts, and including a reciprocating slide arranged adjacent to one end of the beam.

5. In a panic bolt, a pair of oppositely arranged bolts, means for normally causing said bolts to remain projected, means for retracting said bolts comprising a walking beam, links connecting the same with both 90 of said bolts, an operating device connected with said walking beam and comprising a bar arranged transversely of the door, means intermediate said bar and said walking beam whereby movement of said bar toward or 95 from the door moves said beam in a direction to retract said bolts, a second means for operating said bolts comprising a knob operatively connected with said beam, and means whereby said beam and operative connection 100 may move independently of the knob.

6. In a panic bolt, a pair of oppositely arranged bolts, means for normally causing said bolts to remain projected, means for retracting said bolts comprising a walking 105 beam, links connecting the same with both of said bolts, an operating device connected with said walking beam and comprising a bar arranged transversely of the door, means intermediate said bar and said walking beam 110 whereby movement of said bar toward or from the door moves said beam in a direction to retract said bolts, a second means for operating said bolts comprising a knob operatively connected with said beam, means 115 whereby said beam and operative connection may move independently of the knob, and means for dead-locking said knob.
